ROTARY MULTI-VANE POSITIVE DISPLACEMENT PUMP

Edward C. Breinig, Maywood, and Edward V. Manning, Morris Plains, N. J., assignors to Bendix Aviation Corporation, Teterboro, N. J., a corporation of Delaware

Application August 2, 1955, Serial No. 526,032

2 Claims. (Cl. 230—152)

This invention relates to an improved rotary multivane positive displacement pump and more particularly to a novel means and arrangement for precompressing a gaseous medium, such as air, within a cavity in the housing of the pump to a pressure approaching a value equal to the outlet line pressure and including the further feature of providing positive vane sealing between the pump inlet and outlet ports.

Conventional multi-vane pumps of this general type consist essentially of a centrally located radially slotted rotor fitted with sliding vanes which make contact with an internal eccentric housing cavity. In such pumps of conventional design, the charge of gaseous medium or air trapped between the vanes at the instant of inlet cut-off remains at substantially the same low inlet pressure until the instant of discharge opening. At the instant of discharge opening, the trapped charge of gaseous medium or air, in a very short amount of time, must, in such a conventional type pump without built-in precompression, have its pressure increased to the relatively high discharge pressure. This raise in pressure is accomplished chiefly by the reverse flow of previously discharged gaseous medium or air with only a small gain in pressure resulting from the vane movement.

One method which has been used in an attempt to prevent this reverse flow is the utilization of a reed-type valve or a spring bias valve in the discharge port. These valves are intended to seal off the reverse flow and to prevent the release of the gaseous medium or air to be discharged from the pump cavity until some predetermined amount of pressure increase has occurred. The major disadvantage, relative to the use of such valves, is the difficulty in constructing valves of sufficiently high response rates so as to be suitable for use with high speed multi-vane pumps. In addition, any valves which might be employed must necessarily utilize moving parts which are subjected to breakage or wear during operation.

An object of the invention is to avoid the disadvantages incident to the use of such valves by the provision of a rotary multi-vane positive displacement pump in which the vane elements cooperate in a non-symmetrical pump cavity so as to adiabatically compress a gaseous medium or air drawn through an inlet into such cavity to a pressure value sufficiently great as to prevent a back rush of such gaseous medium upon the vane elements opening the cavity to an outlet conduit leading from the cavity.

Another object of the invention is to provide a novel rotary multi-vane positive displacement pump having a pump cavity of such design that the vane elements cooperate to precompress the gaseous medium or air therein prior to its discharge so as to approach or attain a pressure substantially equal to the discharge line pressure.

Another object of the invention is to provide a novel rotary multi-vane positive displacement pump in which the vanes are arranged to cooperate in a pump cavity of non-symmetrical contour and in which the cavity is so designed as to progressively decrease in volume from the

2

inlet to the outlet so as to provide precompression upon rotation of the pump and at a ratio that will provide maximum efficiency under preselected operating conditions or within a preselected range of conditions.

Another object of the invention is to provide a novel rotary multi-vane positive displacement pump in which the vanes acting under centrifugal force are so arranged as to provide during rotation of the pump positive vane sealing between inlet and outlet ports of the pump, at least one vane being in contact with the cavity contour to prevent air flow between the ports at all times so as to prevent a direct leak of relatively high-pressure gaseous medium from the discharge port back to the inlet port and without the necessity for maintaining any rubbing contact or critical clearance between the rotor and the housing cavity surface of the pump.

Another object of the invention is to provide a novel rotary multi-vane positive displacement pump for adiabatically compressing a gaseous medium, such as air, and controlling the release of said compressed medium through an exhaust conduit without the use of spring biased valve means having wearing parts which may readily become worn in operation.

A further object of the invention is to provide a compact air pump of great efficiency in comparison to its size and of such simplicity in construction as to adapt it for manufacture and installation at low cost.

Other objects and advantages of this invention are set forth in the following description, taken with the accompanying drawings; and the novel features thereof are pointed out in the appended claims. The disclosure, however, is illustrative only and we may make changes in detail, especially in matters of shape, size and arrangement of parts within the principle of the invention to the full extent indicated by the broad and general meanings of the terms in which the appended claims are expressed.

In the accompanying drawings which form a part of this specification, like characters of reference indicate like parts in the several views wherein:

Figure 1 is a fragmentary side view, partially in section, of a rotary multi-vane positive displacement pump, embodying the novel features of the present invention;

Figure 2 is a sectional end view of Figure 1 taken along the lines 2—2 and showing the relationship of the rotor and vane assembly in the pump cavity;

Figure 3 is a diagrammatic view illustrating the manner in which the gaseous medium or air entering through the pump inlet is entrapped between vanes of the pump at substantially the same pressure as that entering the inlet port of the pump;

Figure 4 is a diagrammatic view illustrating the manner in which the air entrapped in the pump cavity may be compressed between the pump vanes and the decreasing contour of the pump chamber, and also showing by dotted lines that there is provided a minimum of at least one vane in contact with the cavity contour between the inlet and outlet ports at all times so as to prevent leakage of the relatively high pressure air from the discharge port back to the inlet port;

Figure 5 is an enlarged perspective view of a pump vane.

Referring to the drawing of Figure 1, there is shown a rotary air pump including a power unit 10 and a pumping assembly 11 constructed and arranged to be mounted and driven by the power unit 10.

In the present invention, the power unit 10 comprises an electric motor 12 suitably mounted and enclosed within a hollow housing or casing 13, an end wall 14 closing one end of the housing 13, while the air pump unit 11 is suitably fastened to an opposite end wall 15 or housing 13 by bolts 16.

The pump assembly 11 comprises a casing 17 and a head wall 18. Head wall 18 is secured to the casing 17 and the end wall 15 of the casing 13 by the bolts 16 which pass through tubular openings in the head 18 and casing 17 and screw-threadedly engaged in the wall 15.

Motor 12 is provided with a shaft 21 rotatably mounted in bearings 23 and 25 carried by the end wall 15 and the head 18, respectively. Secured to the shaft 21 by keys 27 for rotation therewith is a cylindrical rotor member 28. End plates 29 and 30 are provided in the end wall 15 and head 18, respectively to sealingly engage the side of the rotor member 28 and rotor vanes 32, 33 and 34 slidably mounted therein, as best shown in Figure 2.

The rotor 28 has formed therein suitable longitudinal slots 36, 37 and 38 each extending, as indicated in Figure 3, tangent to a circle "Z" having a common center to that of the rotor 28 and, as shown in Figure 2, in spaced relation to and in a plane at one side of the shaft 21 and center of rotation of the member 28. Slidably mounted in the slots 36, 37 and 38 and extending from the rotor member 28 at an acute angle to the circumferential surface thereof and in a direction corresponding to the direction of rotation of member 28 are the vanes 32, 33 and 34, respectively. The outer edges of the vanes make contact with a profile of a pump cavity or chamber of oval cross-section formed within the casing 17 and act to seal at all times the pump inlet 40 from the pump outlet 42 so as to prevent back rush of high pressure gaseous medium from the outlet to the inlet through the pump cavity, as shown diagrammatically by Figures 3 and 4. It is to be noted that about one half of rotor is uniformly closely-spaced to one end of the oval-shaped cavity and that a compression chamber of extended crescent cross-section results.

Further, the profile of the cavity has a predetermined contour so designed as to progressively decrease the volume of a portion 39 of the cavity between the inlet 40 and the outlet 42 so that upon rotation of the element 28 gaseous medium drawn into the portion 39 may be entrapped between successive vanes 32, 33 and 34 and pre-compressed prior to release of the gaseous medium through outlet 42.

The contact between the vanes and the profile of the cavity within the casing 17 is maintained by the radial component of the centrifugal force acting on the vanes during rotation of the rotor element 28 so as to maintain the outer edges of the vanes in contacting relation with the profile of the cavity without excessive friction and load at high speeds of rotation, as distinguished from vanes of the true radially extending type in which the centrifugal force applied at high speeds may cause an excessive wear, friction and load to be applied to the outer edges of the vanes increasing with the speed of rotation.

Thus, as the shaft 21 is rotated, gaseous medium such as air may be drawn into the pump cavity and between the vanes, such as 32 and 33, through the pump inlet port, indicated in Figure 2 by the numeral 40, and thereby precompressed and finally delivered to the pump outlet port 42 under the compression force thereof. It is to be noted that the inlet and outlet are opposite each other and in alignment. The oval-shaped pump cavity has its major axis at about a forty-five degree angle to this line of alignment.

Referring to the diagrammatic drawing of Figure 3, a charge of air or gaseous medium is entrapped in the portion 39 of the cavity between the vanes 32 and 33 at substantially the same pressure as that entering the inlet port 40 so as to occupy a volume designated in the drawing of Figure 3 by the letter "X."

Now referring to the drawing of Figure 4, it will be seen that the gaseous medium or air charge between vanes 32 and 33, and indicated by the letter "Y," has now been rotated to a location just prior to its discharge through outlet port 42 and, because of the predetermined non-

symmetrical profile of the portion 39 of the pump cavity of progressively decreasing volume, the charge of gaseous medium "Y" has now been compressed between the vanes 32 and 33 with a consequent increase in pressure.

Theoretically, the charge between the vanes 32 and 33 has been precompressed adiabatically in accordance with a predetermined relationship.

Again referring to the schematic drawing of Figure 4, it can be seen that the relationship of the distance between the inlet port 40 and the outlet port 42 and the distance between any two vanes (indicated by dotted lines in Figure 4) is arranged to provide a minimum of at least one vane in contact with the contour of the pump cavity between the ports 40 and 42 at all times. The importance of this feature is to prevent a direct leak of relatively high pressure air from the discharge port 42 back to the inlet port 40 without the necessity of maintaining any rubbing contact by the rotor 28 and the non-symmetrical cavity surface and, further, without the necessity of maintaining even a critically close clearance between the surfaces of the rotor and housing cavity.

Under our present invention, the gaseous medium or air is squeezed or compressed between vanes of the rotor moving in the portion 39 of the pump cavity prior to the discharge of the air or gaseous medium through the exhaust conduit 42. This is shown by Figures 3 and 4 wherein the air or gaseous medium between the vanes 32 and 33 of the rotor 28 is shown in the process of being compressed. Since the volume of the portion 39 of the pump cavity progressively decreases in volume from the inlet 40 to the outlet 42, it will be seen that prior to release, the pressure of the gaseous medium or air compressed through the above means is increased to such a degree that upon release of the same, as shown in Figure 4, by the dotted line vane 33, there is no backing up or back rush of air, instead the compressed gaseous medium carried in the cavity space 39 separating the vanes 32 and 33 passes directly out the exhaust conduit 42 under the compression force thereof.

Through the use of built-in precompression in a pump of the type described herein, there is provided a pump with relatively constant input torque or power requirements so as to make these pumps ideally suited for use with various driving means, particularly when used under a wide range of operating conditions.

There may be further provided in the subject pump a vane structure and arrangement such as disclosed and claimed in a copending application Serial No. 525,846, filed August 2, 1955, by Walter L. Cable and assigned to Bendix Aviation Corporation, assignee of the present application.

As described in the last-mentioned application, the vanes 32, 33 and 34 are formed of carbon or other suitable material and, as shown in Figure 5, have provided a series of longitudinal holes 50 having openings 52 in the bottom surface of the vane facing the inner end of the rotor slot in which the vane is slidably fitted, as indicated in Figure 2, with a close tolerance between the surfaces of the slot and vane to maintain a minimum leakage path between the slot and vane surfaces.

Upon rotation of the rotor 28, each of the vanes 32, 33 and 34 is forced outwardly into contacting relation with the inner surface of the pump housing causing an increase in the volume of the space at the bottom of the slot between the end of the vane and the inner end of the slot as the vane under centrifugal force moves to its outermost position, as indicated in Figure 4 for example by the vane 32.

In the case of a conventional solid type vane, this volume would normally be negligible if the vane be in its innermost position, as indicated for example by vane 34 of Figure 4, with no additional volume provided at the bottom of the vane or slot of the rotor so that in going from a zero volume to the maximum volume posi-

tion, a suction would be created under the vane which would tend to retard a conventional solid type vane from moving out and properly contacting the inner pump housing surface. Such lack of proper contact of the solid type vane would result in a loss in pumping or volumetric efficiency due to leakage in the pumped air between the vane tip and the profile of the pump cavity in the pump housing.

However, by designing a relief section or volume into the vane by the provision of the holes 50, this suction effect can be minimized. Thus, in effect, the volume built into the vane acts as a variable rate spring which can adjust itself to particular inlet and outlet conditions of operation. This phenomena is particularly effective under low flow conditions in which high pump suction is desired, since it allows a greater efficiency of operation under such conditions than that achieved in a pump of the aforesaid type having conventional type vanes lacking the relief section or excess volume provision.

The advantages of the arrangement with the vane structure illustrated at Figure 5 resides in the fact that such vane structure in minimizing the suction effect on the vanes gives to the pump (1) a much higher flow characteristic under particular operation conditions, (2) a higher pump suction under no flow conditions, and (3) less vane wear due to the decrease in weight obtained by including the relief section or excess volume in the vane itself.

From the foregoing, it will be seen that there has been provided a simple, efficient and improved rotary multi-vane positive displacement pump so arranged as to adiabatically compress a gaseous medium such as air therein and without use of spring biased valve means having wearing parts that may become worn in operation.

Although only one embodiment of the invention has been illustrated and described, various changes in the form and relative arrangement of the parts, which will now appear to those skilled in the art, may be made without departing from the scope of the invention. Reference is, therefore, to be had to the appended claims for a definition of the limits of the invention.

What is claimed is:

1. A rotary multi-vane positive displacement gas pump comprised of a housing having a central smooth-walled cavity of oval cross section, a cylindrical rotor member rotatably mounted in said cavity; said cylindrical rotor member and said oval-shaped cavity being constructed and arranged so that about one half of the cylindrical surface of said rotor member is uniformly closely-spaced to the surface of one end of said oval-shaped cavity and so that an extended crescent-like compression chamber is formed; an inlet opening into one end of said compression chamber; an outlet opposite said inlet opening and connected, adjacent but spaced from the other end of said chamber, to the space between said rotor member and the surface of said cavity where closely-spaced; three equi-spaced longitudinal slots in said rotor member; each of said slots extending tangentially to a circle having a center

common to said rotor; and three vanes slidably mounted in said slots and extending from the rotor member at an acute angle to the circumferential surface of the rotor member and in a direction corresponding to the direction of rotation of the member, said vanes being free to slide inwardly and under centrifugal force; whereby, upon rotation of said member, the edge surfaces of said vanes, under centrifugal force acting upon said vanes, continuously contact the surface of the cavity and hence continuously seal the outlet from the inlet after compressing gas in said crescent-like chamber.

2. A rotary multi-vane positive displacement gas pump comprised of a housing having an inlet, a smooth-walled central cavity, and an outlet; a cylindrical rotor member rotatably mounted in said cavity; said inlet and said outlet being opposite each other and in alignment; said rotor member having its axis of rotation perpendicular to the line of alignment between said inlet and said outlet; said central cavity being of oval cross section and having its major axis at about a forty-five degree angle to the line of alignment between said inlet and said outlet; said cylindrical rotor member and said oval-shaped cavity being constructed and arranged so that about one half of the cylindrical surface of said rotor member is uniformly closely-spaced to the surface of one end of said oval-shaped cavity and so that an extended crescent-like compression chamber is formed; said inlet being connected to one end of said chamber; said outlet opening into the space between said rotor and the surface of said cavity where closely-spaced and adjacent to, but spaced from, the other end of said chamber; three equi-spaced longitudinal slots in said rotor member; each of said slots extending tangentially to a circle having a center common to said rotor; and three vanes slidably mounted in said slots and extending from the rotor member at an acute angle to the circumferential surface of the rotor member and in a direction corresponding to the direction of rotation of the member, said vanes being free to slide inwardly and under centrifugal force; whereby, upon rotation of said member, the edge surfaces of said vanes, under centrifugal force acting upon said vanes, continuously contact the surface of the cavity and hence continuously seal the outlet from the inlet after compressing gas in said crescent-like chamber.
